CHECKING FIXTURE

Joseph C. Drader, Detroit, Mich., assignor to
Michigan Tool Company, a corporation of
Michigan

Application November 15, 1929, Serial No. 407,500

1 Claim. (Cl. 33—174)

This invention relates to testing machines particularly suited for worm generating cutters.

The main objects of this invention are to provide an improved testing machine which will 5 visually indicate a minute irregularity in the surface of a piece of work; to provide a testing machine for accurately checking the angularity of the sides of the teeth of a work unit such as a gear cutter; and to provide a simple and accurate machine of this character which is readily adjustable to test pieces of work which vary 10 in size within a wide range.

An illustrative embodiment of this invention is shown in the accompanying drawings, in 15 which

Fig. 1 is a top plan view of the improved testing machine, with a piece of work in position thereon, and with its position when reversed, shown in dotted outline.

Fig. 2 is a view in front elevation of the same.

Fig. 3 is a fragmentary view in front elevation, with a master gauge form on the work supporting spindle.

Fig. 4 is a sectional view taken on the line 25 4—4 of Fig. 2, looking in the direction indicated by the arrows.

In the construction shown in the drawings, an elongated bed plate frame 5 is provided on its upper side with horizontally disposed parallel ways 6 and 7 which are bounded along their outer sides by upstanding flanges 8 and 9 respectively.

A carriage 10 is slidably mounted on the ways 6 and 7, between the upstanding flanges 8 and 9. Means are provided for resiliently holding down and effecting a predetermined frictional restraint to the sliding movement of the carriage; and said means may comprise vertically disposed studs 11 and 12 which extend upwardly 30 through slots 13 and 14 respectively formed in the bed plate parallel with the ways. The upper ends of the studs 11 and 12 are threaded into the carriage 10 and the heads thereof are in spaced relation to the under side of the bed plate. Bow shaped leaf springs 15 and 16 are interposed between the heads of the studs, and are mounted thereon at their medial points with the ends thereof frictionally bearing against the under side of the bed plate.

The bed plate 5 is also preferably provided with a longitudinally extending, medially disposed guide bar 17 rigidly mounted on the top side thereof by studs 18 and 19 which pass up through suitable apertures in the bed plate and 55 screw into the bar. The carriage is suitably

slotted at each end thereof to snugly fit and slide on said guide bar.

Means is provided for sliding the carriage 10 on its ways, and this means preferably comprises a lead screw 20 journaled against axial movement in an upstanding bracket 21 integrally formed on one end of the bed plate medially of the ways 6 and 7. The screw 20 is threaded into the adjacent end of the carriage 10 and a hand wheel 22 is shown as rigidly secured on the end 10 thereof which projects through the bracket 21, by a nut 23. A sleeve or collar 24 may be interposed between the hand wheel 22 and bracket 21, and indexed to co-operate with a mark on the bracket, for measuring movement of the 15 carriage relative to the bed plate. A knurled headed set screw 25 is shown as threaded in the sleeve 24 for releasably securing it to the screw at any desired circumferential position.

The carriage 10, at its rear side, is provided 20 with an upstanding bracket 26, shown as integrally formed thereon, which has a vertically disposed, parallel sided slot therein which provides guideways 27. The guideways 27 slidably support a gauge frame 28 (see Fig. 1) which is 25 shown as embraced thereby and which is provided with a nut 29 and washer 30 which bear against the rear face of the ways.

The top end of the slot which forms the ways 27 is closed by a crosshead 31 secured by screws 32 to the top end of the bracket 26. The crosshead 31 may snugly receive a vertically disposed lead screw 33 which is threaded through the gauge frame 28 for adjusting said frame vertically with respect to the carriage 10 and bed 35 plate 5. A handle 34, having a pair of upstanding diametrically opposed pins 35 and 36, is shown as rigidly mounted on the top end of the lead screw 33 for facilitating manual rotation thereof.

A visual indicating gauge 37 is rigidly mounted on the frame 28 by a knurled headed screw 38 which passes through a lug 39 on the gauge and is threaded into the frame 28. The indicator 37 is preferably graduated to one thousandth of an inch, and the face thereof is preferably rotatable so that all readings may be taken from zero, if desired.

The gauge frame 28 is shown as provided with an arm 40 integrally formed thereon which extends downwardly and toward the end of the bed plate opposite to the end having the lead screw for moving the carriage. The lower end of the arm 40 has a lever 41 pivoted thereon by a stud screw 42. One end of the lever may be bifur-

cated as shown at 43 to embrace a pin in the lower end of an indicator operating connection 44, and the other end thereof may have the form of a pointer or finger 45, adapted to contact with the surface of the piece of work to be tested, the lever 41 thus serving as part of a connecting means between finger 45 and gauge 37.

Any suitable means may be provided for supporting a work unit to be tested, and the illustrated means comprise an upstanding bracket arm 46 integrally formed on the bed plate 5 at the rear side and adjacent to one end thereof. The upper end of the bracket arm has one end of a suitably disposed work supporting spindle 47 rigidly secured thereto, as by a nut 48, the axis of said spindle being, in the illustrated instance, perpendicular to the plane of movement of the carriage 10. The other end of the spindle is shown as provided with retaining means in the form of a knurled hand nut 49 which abuts against a freely slideable spacing sleeve 50, interposed between the nut and a piece of work 51. The piece of work 51 shown in Figs. 1 and 2 of the drawings is a worm generating cutter in which the teeth 52 thereof have plane sides.

It will be evident that there must be some cylindrical surface to which each straight line element comprised in any tooth surface of the illustrated type is tangent; and any member which provides a surface sustaining this relation to successive corresponding surfaces provided by the teeth of any gear, any gear cutter or like work unit that is to be tested is hereinafter referred to as a "master cylinder" or form,—said member being suitable for use in the zero-setting of the pointer or dial of gauge 37; and, in the operation of this device, it will accordingly be understood that, to establish a tangent plane at the desired level, a master cylinder form 53 may first be placed on the work spindle 47 and the carriage 10 and frame 28 may be moved until the end of the finger 45 is on the top dead center of the cylinder. In thus positioning the finger 45, sufficient pressure is placed thereon by appropriate vertical movement of the gauge frame 28 so that the pointer hand of the gauge will move either way from the set position all back lash or lost motion between parts being taken up. The indicator gauge is then observed and preferably set with a zero reading.

The carriage is then withdrawn by rotating the handwheel 22 and lead screw 20, and the cutter or other work unit to be tested put on the spindle 47 in the place of the master cylinder. The carriage may then be moved until the finger 45, its tip being raised or lowered, if necessary, is brought opposite and into engagement with the outer tip of a cutter tooth and the cutter rotated on the spindle until the reading is again zero. The cutter 51 may then be clamped by the hand nut 49 and the carriage moved forward toward the spindle so as to cause the finger 45 to slide on the surface of the tooth. Depressions or raised spots as well as any error in the angularity of that side of the tooth which is thus tested may be seen by observing the movement, if any, of the pointer on the gauge 37.

Each tooth is successively brought into and held in position as described, and when the same side of each tooth on the cutter has been thus examined, the cutter may be removed from the spindle and replaced in reverse position so that the opposite sides or faces of the cutter teeth may be similarly tested. In thus reversing the cutter, the nut 49 and collar 50 are removed to permit removal of the cutter 51, and before the cutter is replaced in reverse position a suitable spacing collar is placed on the support and is then followed by the cutter, the latter being thus positioned for co-operation with the pointer 45; in case both of the sets of the faces of the teeth 52 are alike, or comprise lines that either should be included in the mentioned tangential plane or should vary therefrom only in a pre-determined manner, the above procedure may then be repeated.

Various sized cutters and pieces of work may be tested on this machine, appropriate to master cylinder forms being used and a corresponding adjustment in any appropriate direction and/or plane being secured, as by moving the gauge frame 28 in its guideways by rotating the lead screw 33 in the appropriate direction.

Although but one specific embodiment of this invention has been herein shown and described, it will be understood that numerous details of the construction shown may be altered or omitted without departing from the spirit of this invention, as defined by the following claim; and that the described method, as applied to a cutter whose tooth surfaces should lie in substantially radial planes, comprises first determining a plane tangent to a cylinder having a fixed axis; zero setting a gauge which is provided with a finger (said finger being then disposed in said plane, as by reason of its engagement with a master form concentric with said axis); thereafter disposing a work unit concentrically with said axis and so that a point in its surface that is to be tested lies in said plane and in engagement with said finger; and producing a relative parallel translatory movement between said unit and said gauge with reference to said plane while observing said gauge.

I claim:

A device for testing the teeth or thread of an element the sides of which are tangent to a circle, which includes, in combination, a base, a finger, an indicator actuated thereby, an arbor upon which the element to be tested may be supported, a cylinder of the same diameter as the base circle of the element to be tested disposable on said shaft for setting the indicator to have the finger disposed to move in a plane tangent to the base circle of said element, means for securing an element to be tested on the arbor to have the side of its tooth in engagement with said finger when the indicator shows said setting, and means for advancing said finger over said tooth or thread to explore the surface thereof.
